G. NIEBEL

ELECTRIC BULB OR SIMILAR ARTICLE

Filed Dec. 20, 1927

Geoffrey Niebel. INVENTOR.

Patented Dec. 4, 1928.

Des. 77,118

UNITED STATES PATENT OFFICE.

GODFREY NIEBEL, OF NEW YORK, N. Y.

DESIGN FOR AN ELECTRIC BULB OR SIMILAR ARTICLE.

Application filed December 20, 1927. Serial No. 24,556. Term of patent 14 years.

To all whom it may concern:

Be it known that I, GODFREY NIEBEL, a citizen of the United States, and resident of New York, in the county of New York and State of New York, have invented a certain new, original, and ornamental Design for an Electric Bulb or Similar Article, of which the following is a specification, reference being had to the accompanying drawing, forming part thereof.

The view is an elevation of an electric bulb or similar article, showing my new design.

I claim:

The ornamental design for an electric bulb or similar article, substantially as shown.

Signed at New York, in the county of New York and State of New York, this nineteenth day of December A. D. 1927.

GODFREY NIEBEL.
